UNITED STATES PATENT OFFICE

110,536

DESIGN FOR AN AUTOGRAPHIC REGISTER

Robert Davol Budlong, Chicago, Ill., assignor to United Autographic Register Co., a corporation of Illinois

Application May 20, 1938, Serial No. 77,319

Term of patent 14 years

To all whom it may concern:

Be it known that I, Robert Davol Budlong, a citizen of the United States, residing at Chicago, county of Cook, and State of Illinois, have invented a new, original, and ornamental Design for an Autographic Register, of which the following is a specification, reference being had to the accompanying drawing, forming a part thereof, in which:

Figure 1 is a plan view of an autographic register; Fig. 2 is a side elevational view; and Fig. 3 is an end elevational view looking toward the left of Fig. 1, showing my new design.

I claim:

The ornamental design for an autographic register, as shown and described.

ROBERT DAVOL BUDLONG.
